THREAD SUCTION DEVICE ON SPINNING
AND TWISTING FRAMESHermann Bühler, Jr., Winterthur, Switzerland, assignor
to Firma Hermann Bühler & Co., A.G., Winterthur,
Switzerland

Filed July 7, 1959, Ser. No. 825,502

Claims priority, application Switzerland Aug. 7, 1958
10 Claims. (Cl. 57—56)

The present invention relates to a thread suction device on spinning frames and twisting frames.

Devices for the thread and dust section are known wherein relatively large slot-like orifices extend over a plurality of spinning stations and are arranged immediately behind the drawing rollers between the roving bobbins and the spinning spindles. In these devices the air stream is led from the orifices to the conduits whose cross sections are nearly uniform at the center of the machine to a ventilator which is covered by a filter. The above mentioned large cross section of the suction orifices facilitate a whirling and purification of large amounts of air at a small pressure gradient and thereby minor consumption of energy.

It was found out in practice that such a device for keeping the spinning and twisting frames clean and thereby the spinning spaces, is extremely suitable, but that the thread suction process after breaking of the thread at the feed drawing roller of the drafting mechanism cannot be satisfactorily controlled.

The device according to the present invention removes these disadvantages. It is provided with a thread and fly suction device having a central casing with channels which are provided with an orifice slot each extending within the range of the drawing mechanism at several working points, and is characterized by suction conduits which are provided within the orifice slot of the channels and the suction openings of which are located closely to the feed drawing rollers.

Advantageously, the suction conduits extend over an entire drawing mechanism system between two stands or bearing points. Thereby the suction conduits may have a constant cross section or may be formed diffusion-like.

According to a special embodiment a means is connected to the orifice slot into which the suction conduit extends, which converts speed energy to pressure. The suction conduit thereby can be extended, freely supported, into the suction orifice without the aid of any packings.

With the above and other objects in view which will become apparent from the detailed description below, some preferred embodiments of the invention are shown in the drawings in which:

FIGURE 1 is a diagrammatical cross-sectional view taken upon section line I—I of FIGURE 2 through a spinning frame illustrating the thread suction device.

FIGURE 2 is a partial diagrammatic front elevational view of the spinning frame shown in FIGURE 1 illustrating the thread suction device.

FIGURE 3 is a partial cross-sectional view upon an enlarged scale showing the drawing mechanism together with the suction means cooperating therewith.

FIGURE 4 is a side view of a detail of the drawing mechanism.

FIGURE 5 is a view similar to FIGURE 1 showing a modified construction of the suction mechanism.

FIGURE 6 is a partial elevational front view of the construction shown in FIGURE 5.

FIGURE 7 is a view similar to FIGURE 1 of a further modification of the suction apparatus.

FIGURE 8 is a front elevational view of the structure shown in FIGURE 7, and

2

FIGURES 9 and 10 show cross-sectional views of two modifications of the suction conduits.

A frame 1 of a spinning frame is provided with longitudinally extending roller beams 2, to which the stands 3 are screwed which support in a known way the driving rollers of a drawing mechanism 6, particularly the feed drawing rollers 4 upon the pressure roller supporting arm 5.

In the center of the machine on the roller beams 2 a known suction casing 8 is supported with symmetrically arranged intake channels 7. The casing 8 ends in the upper part of the machine with a fan 9 therein and a filter 10.

Suction conduits 12 extend into the orifices 11 of the channels 7, said conduits being of smaller cross section since the size thereof is limited by the upper and lower limitation of the orifice 11 and by the height of the supporting feet 13. Because of technical flow reasons, a median altitude level is preferred. The suction conduit 12 itself extends, at the beginning, parallel to the direction of flow within the orifice of the channel 7. Then the conduit 12 is slightly bent upwardly and extends rectilinearly towards the feed drawing roller 4.

The suction opening 14 of the suction conduits 12, as shown in FIGURE 3, widens slightly at the drawing roller 4 towards the bottom and the top and is arranged in such a way, that air is circulated around from both sides, i.e. from the front and towards the back, with nearly the same amount of air. In addition to this, the suction conduit 12 relative to the feed drawing roller 4, is so positioned, that the tangent to the feed drawing roller coincides with the center line of the conduit 12. Because of such positioning any broken thread is within the zone of the highest turbulences in conduit 12 and thereby the highest frictional forces are effective thereon. The width of the conduit 12 corresponds to the distance between two successive stands 3 on which the drawing rollers are mounted.

The suspension of the suction conduit 12 at its suction end which is located near the roller 4 is accomplished by means of offset pin 15, which, on one hand, is welded to the lower side of the conduit 12 or is soldered or fastened in any way, and on the other hand is clamped between two springs 16 and 17, which are secured below to the front surface of a stand 3 by means of a bolt 18. The spring 16 which is adjacent the stand is provided at its upper end with a recess 19 for the insertion of the pin 15, while the other spring 17 is slightly bent towards the front at the top, in order to facilitate an easy insertion of the pin 15 from the front. In this way the conduit 12 can be easily, without the aid of any tools, detached towards the front and again brought to its working position.

Immediately beyond the conduit 12 in the channel 7 there is a diffuser 20 which retards the flow, i.e. converts the speed energy partially into pressure. For the accomplishment of this retarding action a short distance diffuser is suitable whose cross section widens gradually (FIG. 3). The graduated wall 20' of the diffuser is mounted by means of standards 20" on the frame 1. Towards the center of the casing 8 a flap 21 is provided which is secured by means of a screw 23 to a shaft 22 which extends along the machine. The shaft 22 rotates in supports 24 secured to the frame 1 of the machine. A lever 25 which is fixedly connected to the shaft 22 and which is articulated to a lever 26, serves for swinging the flap 21 towards the positions shown in dash lines or dot and dash lines. At a thorough cleaning of the lower located machine parts, for instance by blowing compressed air, the blown off fly are then seized by the medium air stream which is rising towards the top and leads to the filter 10. In order that the thread suction shall continue

its function, the flaps are only adjusted to about $\frac{2}{3}$, i.e. to the position shown in dash lines.

In spinning machines without the conventional belt drive, for instance gear drives, the space between and below the beams 2 is empty and can be used for installing the casing 8', as shown in the modification of FIGURES 5 and 6. The expansion of the casing 8' (FIGURE 6) within the longitudinal direction of the machine is so chosen that the casing can be installed between two intermediate plates 27 forming the frame. In such case, nothing has to be changed at the thread suction conduit 12 which extends to the front drawing roller 4.

FIGURES 7 and 8 illustrate a further embodiment of a casing which is placed at the bottom. It is provided in its upper part at the range of the spindles 29 with vertical walls 30 in order to then taper at half of its height against a suction aggregate (not shown) in a side view (FIGURE 8) which is surrounded by a filter 31. Within the range of the spindles, i.e. where during the winding up process by friction of the ring roller (not shown) parts of the fiber are raised off from the thread, a further horizontal suction conduit 32 is symmetrically arranged which enters with undiminished width into the casing 28 which has not yet tapered at this point. The cross section can be also formed diffusor-like, if this is desired for technical reasons of the flow.

FIGURES 9 and 10 show modified forms of the suction conduit. In the form of FIGURE 9 the suction conduit 33 has a conical diffuser and in FIGURE 10 the conduit 34 is provided with a graduated diffuser 34.

The orifice slot 11 of the channel 7 can, instead of being open, as shown, be closed with the exception of the entry of the suction conduits 12. In this case, the sudden enlargement of the cross section at the entry of the suction conduits 12 into the larger orifice slot 11 acts as an impact diffusor. Naturally, in this embodiment the dust suction effect is not present.

I claim:

1. A thread suction means on a spinning and twisting frame comprising drawing means having feed drawing rollers, a centrally located suction casing, and a flat substantially rectangular suction duct having a suction opening extending uniformly over a plurality of spinning and twisting stations and over the entire width of said duct located adjacent said feed drawing rollers and having an outer opening in the rear end, substantially as large as said suction opening and extending into said central suction casing.

2. A thread suction means on a spinning and twisting frame comprising drawing rollers, a centrally located suction casing having an intake channel projecting toward

said drawing rollers, said channel having an outer opening formed as a slot extending over a plurality of spinning and twisting stations of the frame, and a flat substantially rectangular suction duct having a suction opening extending uniformly over a plurality of spinning and twisting stations and over the entire width of said duct located adjacent said drawing rollers and having an outer opening in the rear end, substantially as large as said suction opening and located in the outer opening of said intake channel.

10 3. A device according to claim 2, wherein the rear end of said suction duct extends with play into the outer opening of said intake channel so that an upper and a lower part of said opening remains free.

15 4. A device according to claim 2 wherein a diffuser means is provided in said intake channel which transforms speed energy into pressure and which constantly expands in the direction of the air flow.

5. A device according to claim 2 wherein said suction duct has substantially a constant cross section and widens shortly before said suction opening.

20 6. A device according to claim 2 wherein said suction duct expands towards its rear end diffusion-like.

7. A device according to claim 2 wherein said suction 25 duct expands step-wise.

8. A device according to claim 2 wherein the distance of the drawing rollers from the front wall and the rear wall of said suction opening of the suction duct are equally large.

30 9. A device according to claim 2 wherein said suction duct extends rectilinearly from said suction opening and then is provided with a bend and extends into said intake channel in the longitudinal direction of the same.

10. A device according to claim 2 wherein said suction 35 duct has a straight section and the center line thereof forms a tangent to the lower drawing roller which is correlated to said suction duct.
